UNITED STATES PATENT OFFICE.

ALBERT CARLSON, OF SWANTON, VERMONT.

GARTER.

Application filed July 13, 1925. Serial No. 43,286.

To all whom it may concern:

Be it known that I, ALBERT CARLSON, a citizen of the United States, residing at Swanton, in the county of Franklin and 5 State of Vermont, have invented certain new and useful Improvements in Garters, of which the following is a specification.

This invention relates to the class of garment supporters and pertains particularly 10 to garters or hose supporters.

The primary object of this invention is the provision, in a manner as hereinafter set forth, of a garter having an improved type of clasp or garment engaging means 15 which can be made to tightly engage the garment without danger of tearing or ripping the same.

Another object of the invention is the provision, in a manner as hereinafter set forth, 20 of a garter having an improved clasp by means of which the garter can be easily and quickly secured in position and after the same has been placed in position and secured, there is no contact between the limb 25 of the wearer and the supporter.

A still further and final object of the invention is the provision, in a manner as hereinafter set forth, of a garter of simple 30 design, strong and durable construction, designed to give satisfactory results and inexpensive to manufacture and produce.

The invention will be best understood from a consideration of the following detailed description taken in connection with the 35 accompanying drawing forming a part of this specification, with the understanding that the invention is not confined to any strict conformity with the showing of the drawing but may be changed and modified 40 so long as such changes and modifications mark no material departure from the salient features of the invention as expressed in the appended claim.

In the drawing:—

45 Figure 1 shows the article embodying this invention, in perspective, in the position assumed by the same when in use.

Figure 2 is a section taken upon the line 2—2 of Figure 1.

50 Figure 3 is a section taken upon the line 3—3 of Figure 1 and,

Figure 4 is a detailed perspective view of one portion of the garter clasp.

55 Referring now to the drawing in detail wherein like numerals of reference indicate corresponding parts throughout the several

views, the garter embodying this invention comprises the usual band of elastic 1, one end of which is looped as indicated at 2 and the end of this looped portion is pressed in 60 the adjusting buckle 3. The other end of the elastic band 1 is secured in the usual fabric or leather pad 4 at one side thereof, and from the other side of this pad there extends a section of inelastic material 5 the 65 free end of which is turned back upon and secured over a stiffening member 6 which extends transversely of the strip 5 as shown.

The looped portion 2 of the band has passed therethrough the enlarged end 7 of a 70 hook member indicated generally by the numeral 8. This hook member as is shown is formed of wire material and the side bars 9 thereof are arranged in spaced parallel 75 relation and connected together at their forward ends as shown and these forward ends are turned back upon the bars 9 to form the end 10 which is substantially flat as is shown and is adapted to engage over the covered stiffening member 6. The other ends of 80 the bars 9 of the hook member flare outwardly at their rear portions as shown in Figure 1 and are then turned inwardly and connected together to provide the loop 7 through which the loop 2 of the elastic material is engaged. 85

Secured to and depending from the lower portion of the pad 4 is a loop of inelastic material 11 in the lower looped portion of 90 which a substantially flat hook member 12 is secured. This hook member is formed of wire-like material and comprises the spaced 95 parallel side members 13 which are turned inwardly and connected across their rear ends as indicated at 14 for engagement through the loop 11, and their forward ends are turned back upon themselves as indicated at 15 and connected across the body of the hook as at 16 to form the flat hook bill shown. 100

The hook bill as shown, is bent intermediate its ends and directed inwardly toward the frame over which it lies to form a constricted portion, this inwardly directed part of the hook bill lying closer to the body than the remainder of the bill. 105

Secured to the pad 4 with the depending looped member 11, is a suspending cord 17 from the lower end of which a locking tongue or finger 18 is supported. This 110 finger is of a rigid material.

When the garter is in position about the

wearer's limb as indicated in Figure 1, with the hook 8 engaging the covered stiffening member 6, the upper edge of the stocking or sock is laid over the bill of the hook 12 and the locking finger is then pressed downwardly between the side portions 13 and the portions 15 of the bill wedging the hose thereinto and holding it by frictional engagement. The hose is thus held securely without danger of tearing.

From the foregoing description it will be readily seen that there has been provided a unique and novel hose supporter which will overcome the annoying fault of some hose supporters of tearing out the top of the hose.

Having thus described my invention what I claim is:—

In a garter of the character described, a

clasp adapted to be connected to the garter to be suspended therefrom and including a loop made from a single piece of wire bent to provide a substantially flat frame having one end turned outwardly and upwardly to form a broad hook bill overlying said frame in close relation thereto for a considerable distance thereof, said bill having its intermediate portion directed inwardly toward the frame to form a constricted portion, and a locking tongue formed from a flat elongated plate adapted to be engaged crosswise between said bill and frame and having flexible connection with the garter above the clasp.

In testimony whereof, I affix my signature hereto.

ALBERT CARLSON.
